METHOD OF MAKING STRUCTURAL FORM TIES

Robert Clyde Gates, Denver, Colo., assignor to Gates & Sons, Inc., Denver, Colo., a corporation of Colorado

Application March 28, 1952, Serial No. 279,873

2 Claims. (Cl. 140—73)

This invention relates to methods of making structural form ties and has reference more particularly to a method of making form ties of the construction shown and described in U. S. Patent 1,692,166 of November 20, 1928.

The tie described and claimed in the patent above identified has many desirable features but was not manufactured in large numbers until lately when a practical method of manufacture was invented.

It is the object of this invention to disclose and claim a practical method of manufacturing the tie described in the above identified patent.

In order to describe the method reference will be had to the accompanying drawing in which the products of the several steps have been illustrated in the order in which they are performed by the method.

Figure 1 is a view showing a length of a wire as it appears after it has been subjected to the first step of the method;

Figure 2 is a top plan view showing the appearance of the wire at the end of the second step;

Figure 3 is a side elevational view of the wire shown in Figure 2; and

Figure 4 is a top plan view of the completed form tie.

Referring now to the drawing reference numeral 10 designates a wire that has been subjected to the first step of the method by which the ends are formed into hooks by first bending the wire at point 11 into an obtuse angle u ; the wire is then bent reversely at 12. The end 13 extends at right angles to the length of the wire. The original length of the wire is divided into three equal lengths or approximately so, and these points are marked in some suitable manner and have been designated by numeral 14 in Figure 2.

When the method is performed manually, the wire is reversely bent at points 14 into the shape shown in Figure 2. After this second step has been completed the ends 13 of the hooks extend at right angles to the plane of the bight 15 and are located between the sides of the bights as shown in Figure 2. The wire which is now in the form illustrated in Figures 2 and 3 is then grasped at the bights and the hooked ends are held in approximately the position shown in Figure 3 with the ends 13 extending equal distances on both sides of the planes of the bights. The two bights are now subjected to a relative rotary movement which twists that portion between the hooked ends into a cable as shown in Figure

2

4. Due to the fact that the material has some resiliency the twisting is carried through more than a number of complete turns so that when the torque is released the parts will turn in the opposite direction through an angular distance that brings ends 13 substantially into the same plane.

What makes it possible to make these ties by machine is that the ends are formed into hooks by the first step. After the ends are formed into hooks the machine, when 10 one is used, holds the ends in parallel relation and makes it possible and practical to hold the hook ends perpendicular to the planes of their associated loops during the twisting operation.

The discovery that the hooks must be made at the first 15 step in the operation made it possible to construct a practical machine for the automatic manufacture of the ties and it is to this feature or step of the method that this method is directed.

Having described the invention what is claimed as new is:

- 20 1. The method of making a structural form tie from a straight wire of a length approximately three times the length of the finished tie which comprises the following steps performed in the order given; bending the ends of the wire into the forms of hooks whose ends extend across the line of the wire; folding the wire simultaneously about two points which divide the original length of the wire into three equal parts thus forming a bight at each end, the reversely bent portions that terminate in the hooks 25 crossing each other, thereby positioning the hooks in the bights, the planes of the hooks being parallel and substantially perpendicular to the planes of the bights; and twisting all of that part between the hooks into a three strand cable.
- 25 2. That method of forming a concrete form tie from a straight piece of wire three times the length of the finished tie which comprises, bending the ends of the wires into hooks whose end portions are substantially co-planar and extend substantially equal distances on 30 each side of the line of the wire, folding the ends of the wire simultaneously about two points equidistantly spaced from the hooks and spaced from each other a distance substantially equal to one third the length of the wire, the reversely folded portions terminating with the end of the hook on one end positioned in the bight at the other end, and twisting the three wires in the space between the 35 hooks forming them into a cable.
- 35 40 45
